DESIGN FOR A TELEVISION RECEIVER

Johan C. Kromhout, Forest Hills, N. Y., assignor
to Sylvania Electric Products Inc., a corpora-
tion of Massachusetts

Application May 9, 1947, Serial No. 138,935

Term of patent 14 years

(Cl. D56—4)

To the Commissioner of Patents:

Be it known that I, Johan C. Kromhout, a citizen of the United States of America, residing at Forest Hills, in the county of Queens, in the State of New York, have invented a new, original, and ornamental Design for a Television Receiver, of which the following is a specification, reference being had to the accompanying drawings, forming a part thereof, in which:

Fig. 1 is a plan view of the television receiver embodying my new design;

Fig. 2 is a front elevation of the television receiver;

Fig. 3 is a side elevation, and

Fig. 4 is another side elevation showing my new design, the rotatable and pivotably hinged

tube housing forming a part of the television receiver being tilted slightly downward and directed slightly to the side.

The characteristic features of my design are shown in solid lines in my drawing.

What I claim is:

The ornamental design for a television receiver, substantially as shown and described.

JOHAN C. KROMHOUT.
